Primary Examiner — Vy N Koenig*Assistant Examiner* — Michelle M Reeves(74) *Attorney, Agent, or Firm* — ScienBiziP, P.C.(57) **CLAIM**

The ornamental design for a toilet paper holder, as shown and described.

DESCRIPTION

FIG. 1 is a front, right and top perspective view of a toilet paper holder, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the toilet paper holder in a closed state.
 The broken lines shown in the drawings are included for the purpose of illustrating portions of the toilet paper holder that form no part of the claimed design.
